UNITED STATES PATENT OFFICE.

CHRISTIAN WILLIAM MEINECKE, OF JERSEY CITY, NEW JERSEY, AS-
SIGNOR TO MEINECKE & CO., OF NEW YORK, N. Y., A CORPORATION
OF NEW JERSEY.

DESIGN FOR A RECEPTACLE OR VESSEL.

SPECIFICATION forming part of Design No. 37,300, dated January 24, 1905.

Application filed December 15, 1904. Serial No. 237,038. Term of patent 14 years.

To all whom it may concern:

Be it known that I, CHRISTIAN WILLIAM MEINECKE, a citizen of the United States, residing at Jersey City, in the county of Hudson and State of New Jersey, have invented a new, original, and ornamental Design for a Receptacle or Vessel, of which the following is a specification.

This invention relates to a new, original, and ornamental design for receptacles or vessels, and is illustrated in the annexed drawings, in which—

Figure 1 shows a side elevation of a vessel embodying this design. Fig. 2 is a plan view of Fig. 1.

What I claim as new, and desire to secure by Letters Patent, is—

The ornamental design for a receptacle or vessel substantially as herein shown.

CHRISTIAN WILLIAM MEINECKE.
